CLAIM

(21) Appl. No.: **29/142,335**

The ornamental design for a surface pattern for a disposable absorbent article, as shown and described.

(22) Filed: **May 23, 2001**

DESCRIPTION

(51) LOC (7) Cl. **24-04**

The FIGURE is a top plan view of a surface pattern for a disposable absorbent article, showing our new design.

(52) U.S. Cl. **D24/125; D24/124**

The broken line showing is for illustrative purposes only and forms no part of the claimed design.

(58) Field of Search **D24/124, 125; 604/358, 378, 379, 380, 383, 384, 385.01, 386, 387; D5/47, 53, 54, 56, 57, 60-62,**
